(57) **CLAIM**

I claim the ornamental design for a breath deflector for helmet, as shown and described.

DESCRIPTION

FIG. 1 is a front perspective view of a breath deflector for helmet showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view of the breath deflector for helmet taken in the direction of line 8-8 in FIG. 2; and,
FIG. 9 is another front perspective view of the breath deflector for helmet shown in a state of use in which the helmet is provided in broken lines to illustrate example environment.

The broken lines in the figures depict portions of the breath deflector for helmet which form no part of the claimed design.

The dot-dash broken lines in the figures represent a boundary of the claimed design and form no part thereof.
